(57) **CLAIM**

I claim the ornamental design for a multi-purpose tool, as shown and described.

DESCRIPTION

FIG. 1 is a front elevational view of a multi-purpose tool.

FIG. 2 is a rear elevational view thereof.

FIG. 3 is a side elevational view thereof.

FIG. 4 is an elevational view of a side opposite that shown in FIG. 3.

FIG. 5 is a top plan view thereof; and,

FIG. 6 is a bottom plan view thereof.

The broken line depiction of the multi-purpose tool is for the purpose of showing portions of the multi-purpose tool and forms no part of the claimed design.

Any portion of the tool handle between the break lines forms no part of the claimed design.
